UNITED STATES PATENT OFFICE.

WILLIAM D. BUNNY, OF TROY, NEW YORK.

DESIGN FOR A FLOOR-POLISHER.

41,495.

Specification for Design. Patented June 20, 1911.

Application filed March 3, 1910. Serial No. 547,169. Term of patent 7 years.

To all whom it may concern:

Be it known that I, WILLIAM D. BUNNY, a citizen of the United States, residing at Troy, in the county of Rensselaer and State of New York, have invented a new, original, and ornamental Design for Floor-Polishers, of which the following is a specification, reference being had to the accompanying drawing, forming part thereof.

Figure 1 of the drawings is a view in perspective of a floor-polisher showing my new design. Fig. 2 is a view in perspective of the same inverted.

A leading feature of the design consists in

the U-shaped form of the back of the polisher and the semi-cylindrical curved ends of the brush or body of the polisher, there appearing at each end side by side, a comparatively large and a comparatively small semi-cylindrical column.

I claim:—

The ornamental design for a floor-polisher, as shown and described.

WILLIAM D. BUNNY.
